ATTORNEY.

UNITED STATES PATENT OFFICE.

GOTTFRIED GRILL, OF BALTIMORE, MARYLAND.

CIRCULAR-SAW GUARD.

SPECIFICATION forming part of Letters Patent No. 245,816, dated August 16, 1881.

Application filed June 17, 1881. (No model.)

To all whom it may concern:

Be it known that I, GOTTFRIED GRILL, of Baltimore city, State of Maryland, have invented certain new and useful Improvements 5 in Circular-Saw Guards; and I hereby declare the same to be fully, clearly, and exactly described as follows; reference being had to the accompanying drawings, in which—

Figure 1 is a side elevation of the device; 10 Fig. 2, a sectional view on the line xx of Fig. 1, and Fig. 3 is an elevation of the wheel for opening the kerf.

The object of my invention is to furnish a 15 guard to prevent injury to the operator in using a circular saw, whether arising from cutting of the hands by the saw or from the lumber being thrown up by the farther or rising edge of the saw; and my said invention consists in certain features of construction and combinations of parts as hereinafter set forth and 20 claimed.

In the drawings, A is a frame made fast to the ceiling above the saw; and B is a bar which 25 passes through a slot in the frame, and is secured at any desired elevation by a set-screw, g.

D is a cross-head secured to the bar B, and to it are hinged at d braces C C, that are secured by clamping-screws at either side of the frame A, as shown.

To the lower end of the bar B is pivoted at 30 b a pair of arms, $a a'$, curved to conform to the periphery of the saw, and having sides which inclose the saw-teeth. In the arms $a a'$ telescope supplemental arms $c c'$, also arranged to 35 inclose the saw-teeth, which arms are clamped by set-screws l l. The arm c' projects in the plane of the saw, constituting a presser-foot, j, to hold down the lumber, and in slots h in its end is mounted a sharp-edged wheel, i, ar- 40 ranged to enter and spread the saw-kerf.

To the arms $a a'$ are attached bars e e, curved

in the arc of a circle about the pivot b, which arms pass through a slot in the bar B and are secured by a set-screw, f.

It will thus be seen that the arms $a a'$, being 45 pivoted to the bar B and having extensible arms $c c'$, are adapted to fit upon saws of various sizes, and the vertical adjustment of the bar B meets any requirement arising from the raising or lowering of the saw with reference 50 to the table.

The presser-foot j holds down the lumber at the exit side of the saw and obviates all danger of the lumber being carried up by the saw, which danger is greatly lessened, independ- 55 ent of the presser-foot, by the wheel i.

The device may readily be applied to circular saws already in use, and will prevent many injuries which without it are very liable to occur.

The wheel i may be readily removed from the slot h, when desired, and a thinner or thicker one inserted, as may be required.

What I claim is—

1. In combination with the bar B, the arms 60 $a a'$ pivoted to its lower end, and extensible arms $c c'$, as and for the purpose set forth.

2. In combination with the bar B and arms $a a'$ pivoted to its lower end, the extensible arms $c c'$, the latter having a presser-foot, j, as 70 set forth.

3. In combination with the bar B, the arms arms $a a' c c'$, presser-foot j, and wheel i, as set forth.

4. In combination with the bar B, having 75 pivoted arms C, the arms $a a'$, bars e, set-screw f, and extensible arms $c c'$, having presser-foot j and wheel i, as set forth.

GOTTFRIED GRILL.
